(57) **CLAIM**

The ornamental design for a controller for an optical fiber, as shown and described.

DESCRIPTION

FIG. 1 is a first perspective view of a controller for an optical fiber of the design;

FIG. 2 is a second perspective exploded view of the design showing male and female components;

FIG. 3 is a left side elevational view of the female component of the design;

FIG. 4 is a right side elevational view of the female component of the design;

FIG. 5 is a front side elevational view of the female component of the design;

FIG. 6 is a rear side elevational view of the female component of the design;

FIG. 7 is a top plan view of the female component of the design;

FIG. 8 is a bottom plan view of the female component of the design;

FIG. 9 is an enlarged left side elevational view of the male component of the design;

FIG. 10 is an enlarged right side elevational view of the male component of the design;

FIG. 11 is a front side elevational view of the male component of the design;

FIG. 12 is a rear side elevational view of the male component of the design;

FIG. 13 is a top plan view of the male component of the design;

FIG. 14 is a bottom plan view of the male component of the design; and,

FIG. 15 is a top plan view corresponding to the view of FIG. 1 of the design.

Each of the Figures is shown at an enlarged scale. The broken lines are included for the purpose of illustrating portions of the controller for an optical fiber that form no part of the claimed design.
